(57) CLAIM

The ornamental design for a lighter as shown and described.

DESCRIPTION

FIG. 1 is a perspective view showing a front, top and right side of the lighter in an extended position.

FIG. 2 is a perspective view showing a rear, top and right side of the lighter in the extended position.

FIG. 3 is a right side elevational view of the lighter in the extended position.

FIG. 4 is a left side elevational view of the lighter in the extended position.

FIG. 5 is a top plan view of the lighter in the extended position.

FIG. 6 is a bottom view of the lighter in the extended position.

FIG. 7 is a front end view of the lighter in the extended position.

FIG. 8 is a rear end view of the lighter in the extended position.

FIG. 9 is a perspective view showing a front, top and right side of the lighter in a folded position.

FIG. 10 is a perspective view showing a front, top and left side of the lighter in the folded position.

FIG. 11 is a right side elevational view of the lighter in the folded position.

FIG. 12 is a left side elevational view of the lighter in the folded position.

FIG. 13 is a top plan view of the lighter in the folded position.

FIG. 14 is a bottom view of the lighter in the folded position.

FIG. 15 is a front end view of the lighter in the folded position; and,

FIG. 16 is a rear end view of the lighter in the folded position.

The broken lines in the drawings depict portions of the lighter that form no part of the claimed design.

1 Claim, 10 Drawing Sheets
